UNITED STATES PATENT OFFICE.

WILLIAM OTT, OF CHICAGO, ILLINOIS.

SOFA-BEDSTEAD.

SPECIFICATION forming part of Letters Patent No. 302,863, dated July 29, 1884.

Application filed September 24, 1883. (No model.)

To all whom it may concern:

Be it known that I, WILLIAM OTT, a citizen of the United States, residing at Chicago, in the county of Cook and State of Illinois, have 5 invented certain new and useful Improvements in Sofa-Bedsteads; and I hereby declare the following to be a full, clear, and exact description of the same.

My invention relates to that class of lounges 10 and sofas which may be extended to form a bed, and is in the nature of an improvement upon the bed-lounge patented to me by Letters Patent of the United States No. 186,608, dated January 23, 1877. That patent shows a 15 sofa-bedstead provided with a head-rest consisting of extensible rods F, for the purpose of sustaining the bolster, the rods being pivoted to the inner part of the lounge, and resting, when extended, upon the head-boards of the 20 bed. They are folded within the lounge when the same is closed. By this construction, however, the head-rest is hard and uncomfortable; and the object of my present invention is to provide a head-rest, to be used in connection 25 with a sofa-bed, which, while retaining the advantages of the one formerly patented to me, will overcome the incidental discomfort and inconvenience before set forth; and to this end my invention consists in the construction 30 which I give to the extensible support for the bolster, whereby it is supported out of contact with the head-piece of the frame, and acquires a yielding and elastic character.

In the drawing the figure is a perspective 35 view of a sofa-bed provided with my improve-

ment, a part of the upholstering being removed.

B is the support for the bolster, consisting of rods bent and pivoted to the frame, as in my said former patent, whereby when turned 40 up they extend beyond the end of the lounge and lengthen it.

Instead of having the rods B rest upon the head-piece when turned up, as was the case with the device described in my said former patent, I 45 form them of elastic metal, sufficiently slender to yield easily, and bend them to the form of an elbow near the pivots u, as shown at s, to afford a fulcrum and maintain them out of contact with the head-piece. Ordinarily, two 50 supports are used with each lounge, as represented in my former patent, above referred to.

What I claim as new, and desire to secure by Letters Patent, is—

In a sofa-bed, the combination, with the 55 frame thereof, of the support B for the bolster, formed of a spring-metal rod pivoted to bearings above the frame, as shown at u, and bent to an elbow near each pivot, as shown at s, whereby when the rod is turned outward the 60 elbows bear upon the frame and support the rod in an inclined position, substantially as described.

WILLIAM OTT.

In presence of—

DOUGLAS DYRENFORTH,
ADELBERT HAMILTON.
